INVENTOR

Walter C. Lindemann
BY his ATTORNEY *S.J. Cox.*

UNITED STATES PATENT OFFICE.

WALTER C. LINDEMANN, OF MILWAUKEE, WISCONSIN.

RESERVOIR FOR OIL STOVES.

1,417,672.

Specification of Letters Patent. Patented May 30, 1922.

Application filed October 18, 1920. Serial No. 417,743.

To all whom it may concern:

Be it known that I, WALTER C. LINDEMANN, a citizen of the United States, and a resident of the city of Milwaukee, in the county of Milwaukee, State of Wisconsin, have invented certain new and useful Improvements in Reservoirs for Oil Stoves, of which the following is a specification.

The improvements relate to reservoirs for oil stoves of the student lamp type, and are in the nature of improvements in the construction described and shown in United States Letters Patent No. 1,120,827, of December 15, 1914.

It sometimes happens that the ring or band mounted on the stove frame and supporting the bottle constituting the main reservoir becomes bent so that it does not support the bottle in the proper position with respect to the auxiliary reservoir or sub-tank. If this ring or band is bent downwardly the valve at the bottom of the main reservoir is too low, and the liquid fuel does not rise to the full height in the burner, and if it is bent up the sub-tank fills to a higher level than is desirable and the liquid rises above the proper height in the burners, and may even overflow at the burners. It is desirable therefore that the proper relationship between the bottle supporting band and the sub-tank shall be maintained, and to that end the present improvements provide a gauge to determine this relationship and prevent the parts from getting out of adjustment.

As the frames of these stoves are commonly made of relatively thin sheet metal, and the main supply pipe for liquid fuel, running from the tank to the burners, is supported thereby, there is also danger that the frame will yield to a sufficient extent to permit this supply pipe to become slightly depressed, thereby putting the pipe and the burners supported thereon out of proper adjustment and relation to the tank. The present improvements therefore provide means for reinforcing the end plate of the stove frame at the point where the supply pipe passes therethrough, so that its proper position and relationship to the main tank and sub-tank will be insured.

The present improvements are designed to secure these advantages, and others which will be apparent to those skilled in the art.

The improvements are illustrated in the accompanying drawings, in which Figure 1 is a perspective view of the end plate of a

stove frame with tank and supply pipe supporting means embodying the improvements mounted thereon; Figure 2 is a detail in perspective of the gauge and connection between the tank supporting ring and the sub-tank; Figure 3 is an end view of a portion of the frame plate showing the pipe supporting means in detail; Figure 4 is a vertical section thereof on the line 4—4 of Figure 3; Figure 5 is a detail in perspective of the carrying bail and band of the main reservoir.

A represents the end plate of the frame of a liquid hydrocarbon stove, which may be provided with fixed or vertically adjustable burners of the wickless type or with wick burners. B indicates the main liquid hydrocarbon tank or reservoir, commonly called the bottle, which is usually made of glass in order that the level of liquid therein may be easily observed. C is the auxiliary reservoir or sub-tank, into which the liquid of the main reservoir is automatically discharged, after the manner of the well known student lamp tank, the mouth of the bottle being provided preferably with a spring valve of the character of that shown in the patent above mentioned.

The main reservoir has an annular groove B', which receives and holds a metallic band K with extending portions K', by means of which it is supported vertically and laterally on the ring D. Two of these loops K' also receive ends of the bail L for lifting and carrying the bottle B. The ring D is in turn supported, so as to hold the main reservoir in its proper relation, by the bracket E secured to the end plate A. The auxiliary reservoir C is supported from the end plate by arms F, each secured at one end to the said end plate and at its outer end to the auxiliary reservoir. This reservoir is also supported by the main fuel supply pipe G connected therewith near its bottom and extending therefrom through the end of the stove frame.

To the outer part of the supporting ring D the upper end of the member H is secured, and this member extends downwardly therefrom and inwardly to a point inside the annular rim or flange C' of the auxiliary reservoir, and through the opening therein. The lower end of the member H has two opposed angular recesses cut therein so that its extremity has a T-shape, and the flange C' of the auxiliary reservoir has a slot C² there-in approximating the shape of an ordinary key hole, the lower part of the slot being

narrow and the upper part widened. By means of this provision the T-shaped end of the member H may be inserted through the slot, if the member is turned at about right angles to its normal position, and then turned, so that it is securely held by the engagement of its said extremity with the metal surrounding the slot and the engagement of the narrow portion of the T with the edges thereof, and then when the supporting ring H and its bracket are in proper position, and the latter is secured to the stationary frame a connection is formed which insures that the said ring and auxiliary reservoir, and main reservoir supported on the former, shall be in proper position and relation. This provision is of great advantage not only because it insures the proper relationship of the parts mentioned, but because in making and assembling the reservoir parts the ring D, bracket E and member H may be stamped or otherwise formed, and in large quantities, with absolute accuracy as to size and shape, and united in any suitable manner, so as to form one piece in effect, then mounted in position by simply passing the T-shaped end of the member H through the slot C² while the said parts are at approximately right angles to their normal position, then swinging them around to proper position and securing the bracket to the stove frame.

The means for positioning the main supply pipe G comprise a removable insert J fitted into a vertical aperture A', cut out of the lower portion of the end plate A and provided with flanges J' along its side edges, terminating in tongues J², and small transverse slots A² in the end plates receiving these tongues. The upper end of the aperture A' has a substantially semi-circular recess A³ which receives the upper side of the pipe G.

In assembling these parts, the pipe G, which has previously been secured to the sub-tank C, is passed through the aperture A' and seated in the recess A³, and the sub-tank and pipe therein secured in position by means of the arms F, which may first be secured to the sub-tank and then in this last operation secured to the end plate. This construction and arrangement enables the manufacturer to form and connect these parts before applying them to the stove. The insert J is then placed in the aperture and the tongues J²—which are slightly offset—passed through the slots A², and the insert or slide pressed upwardly until the pipe is firmly clamped, and this part then secured in position by means of screw bolts J³ passing through the flanges of the insert and the end plate. The insert or slide J has an inwardly turned flange J⁴ at its bottom, the sides of which overlie the bottom flange A⁴ of the end plate, so that in this manner the

bottom flange is made substantially continuous and additional strength and support given to the structure.

What I claim is:

1. In a device for supplying fuel to liquid hydro-carbon stoves, the combination of a frame member, a reservoir comprising a main reservoir with bottom opening and an auxiliary reservoir surrounding said opening, a support secured to said frame member and extending around the main reservoir above the auxiliary reservoir, and a connecting member between said support and auxiliary reservoir having a fixed connection with one and a detachable connection with the other. 70

2. In a device for supplying fuel to liquid hydro-carbon stoves, the combination of a frame member, a reservoir comprising a main reservoir with bottom opening and an auxiliary reservoir surrounding said opening, a support secured to said frame member and extending around the main reservoir above the auxiliary reservoir, and a connecting member between said support and auxiliary reservoir having a fixed connection with one and a detachable connection with the other, and said detachable connection, comprising a T-shaped extremity with which the connecting member is provided and the other part being provided with a slot having an enlargement. 85

3. In a device for supplying fuel to liquid hydro-carbon stoves, the combination of a frame member, a reservoir comprising a main reservoir with bottom opening and an auxiliary reservoir surrounding said opening, a support secured to said frame member and extending around the main reservoir above the auxiliary reservoir, and a connecting member between said support and auxiliary reservoir having a fixed connection with one and a detachable connection with the other, and said detachable connection, comprising a T-shaped extremity with which the connecting member is provided and the other part being provided with a slot having an enlargement, 100

<

nection, comprising a T-shaped extremity with which the connecting member is provided, and the other part being provided with a slot having an enlargement, the width 5 of the T-shaped member being greater than one dimension of the slot, but smaller than another dimension, whereby when the said member is passed therethrough and turned it cannot be withdrawn therefrom, the said 10 last named position being the normal position of the parts when assembled for use.

5. In a device for supplying fuel to liquid hydro-carbon stoves, the combination of a frame member, a reservoir comprising a 15 main reservoir with bottom opening and an auxiliary reservoir surrounding said opening, a support secured to said frame member and extending around the main reservoir above the auxiliary reservoir, and a connecting member between said support and auxiliary reservoir having a fixed connection with one and a detachable connection with the other, a supply pipe communicating with the lower part of the auxiliary reservoir 20 and extending laterally therefrom, and through said frame member and a removable device on said frame member and adjustably connected therewith, having a portion capable of being pressed against the supply 25 pipe to hold the same in fixed relation to said frame member.

6. In a device for supplying fuel to liquid

hydro-carbon stoves, the combination of a frame member, a reservoir comprising a main reservoir with bottom opening and an auxiliary reservoir surrounding said opening, a support secured to said frame member and extending around the main reservoir above the auxiliary reservoir, and a detachable connecting member between said support and auxiliary reservoir engaging both of said parts and holding them in fixed spaced relation.

7. The combination of a liquid fuel reservoir having an open top and a lower outlet, 45 means for supporting the same on the frame of a stove, and auxiliary means for supporting and facilitating the assemblage of the parts comprising a supply pipe extending laterally from the reservoir outlet, a frame 50 member having an aperture therein through which said supply pipe extends, said aperture extending beyond the pipe, a removable member secured in said aperture and adjustable to and from the said pipe, whereby 55 the pipe may be passed freely through the said aperture and secured therein between the said removable member and the edge of the aperture.

Witness my hand this 8th day of October, 60 1920, at the city of Milwaukee, in the county of Milwaukee, State of Wisconsin.

WALTER C. LINDEMANN.
